Patented July 27, 1976

240,689

CABINET FOR VIDEO EQUIPMENT OR THE LIKE

Richard J. Warneke, 915 W. Miner St.,
Arlington Heights, Ill. 60005

Filed July 29, 1974, Ser. No. 492,461

Term of patent 14 years

Int. Cl. D6—04

U.S. Cl. D6—174

FIG. 1.

FIG. 2.

FIG. 3.

FIG. 4.

FIG. 5.

FIG. 1 is a front, top and left side perspective view of a cabinet for video equipment or the like showing my new design;

FIG. 2 is a front elevational view;

FIG. 3 is a top plan view;

FIG. 4 is a left side elevational view; and

FIG. 5 is a rear elevational view.

I claim:

The ornamental design for a cabinet for video equipment or the like, substantially as shown and described.
